Primary Examiner — Patricia A Palasik*(74) Attorney, Agent, or Firm* — Batt IP A Law Corporation; Richard Batt(57) **CLAIM**

The ornamental design for an oil midpan as shown and described.

DESCRIPTION

FIG. 1 is a top view of an oil midpan showing our new design;

FIG. 2 is a right-side view of the oil midpan shown in FIG. 1;

FIG. 3 is a left-side view of the oil midpan shown in FIG. 1;

FIG. 4 is a front view of the oil midpan shown in FIG. 1; FIG. 5 is rear view of the oil midpan shown in FIG. 1; and, FIG. 6 is an upper front perspective view of the oil midpan shown in FIG. 1.

The broken lines in the drawings depict portions of the oil midpan which form no part of the claimed design.
